CARBURETOR

Andrew Craig Russell, Shawnee, Okla.

Application August 21, 1946, Serial No. 691,944

1 Claim. (CL 261—14)

1

This invention relates to devices for use with internal combustion engines using a liquid fuel, for converting the liquid into a mist or vapor and for mixing the vapor with air in such proportions that the mixture will burn instantly when introduced to the cylinders of the engine.

The primary aim of this invention is to provide a carburetor that will mix the fuel with air under wide variations of engine speed and power; that will vaporize the mixture under all differences in temperature; that will respond immediately to a demand for greater or less speed; and that will operate efficiently in all such respects in spite of variations in the quality of the fuel used.

One of the most important aims of this invention is to provide a carburetor in the nature of that disclosed in my previously issued U. S. Letters Patent No. 2,366,056, dated December 26, 1944, but which improves on said carburetors to the extent of being appreciably more efficient, considerably less complicated and expensive to manufacture and maintain in working condition, and capable of presenting a unit that is less bulky, lighter in weight, and more positive in its operation in response to the requirements of the engine with which it is used.

An important aim of this invention is to provide a carburetor having means for introducing a continuous charge of heated air to the series of passages for directing air toward the surface of the raw fuel in the mixing chamber thereof which air is in addition to the final means of combining air with the fuel mixture and supplants the compartment for heated fluid usually provided to heat the mixture prior to its passage into the engine, and thereby insuring complete carburation and causing perfect combustion within the cylinders of the engine.

A further aim of this invention is to provide a carburetor having means for introducing heated air emanating from the exhaust manifold of the engine to the surface of the fuel within the mixing chamber for causing carburation immediately upon impingement of the heated air on the fuel, whereby saturation is complete prior to the passage of the mixture through a final flow of air, or to the engine directly as the case may be.

Other aims include the manner of construction of a carburetor of the aforementioned type for permitting such introduction of heated air in combination with the normal supply of air flowing therethrough; the unique manner of causing the flow of both channels of air, the raw fuel, and the mixtures during different stages of carburation through the carburetor through suction in-

2

herent in the engine; and the means of combining the novel features of my previously disclosed devices with the improved heating structure of my present invention.

Other aims will be made clear or become apparent during the course of the following specification, referring to the accompanying drawing wherein:

Fig. 1 is a top plan view of a carburetor made in accordance with my present invention.

Fig. 2 is a side elevational view thereof.

Fig. 3 is a fragmentary sectional view taken on line III—III of Fig. 1.

Fig. 4 is a vertical fragmentary sectional view taken on line IV—IV of Fig. 1; and

Fig. 5 is an enlarged, fragmentary, detailed, cross-sectional view taken through the mixing chamber of the carburetor per se.

A sectional casing 10, when assembled presents an air intake 12, an air outlet passage 14, and a conduit 16 in communication with the air outlet passage 14, forming a compartment for final mixing prior to introduction of the mixture into the engine with which the carburetor is used. A pipe 18 leads from this passage 14 to the intake manifold of the internal combustion engine, not herein shown.

A butterfly valve is disposed within the pipe 18, and although not illustrated, it may take any of the conventional forms and is mounted upon an axle 22 extending exteriorly to a connection with an operating lever 24. This lever 24 is joined to a throttle accessible to the operator whereby the speed of the engine is controlled by opening and closing the butterfly valve. A butterfly valve 26 in passage 12 controls the amount of air entering the carburetor therethrough.

A bowl 28 forms a part of the casing 10 and receives raw fuel from a fuel pipe, not shown, inserted in opening 30. An excessive flow of fuel into the bowl 28 is prevented by a float 32 that rises to close a valve 33 as fuel reaches predetermined point in the bowl 28.

A chambered mounting 34 within the bowl 28 is secured to the underside of the casing 10 that supports the bowl 28 and a plate 36 closes the bottom thereof as is clear in Figs. 3 and 4. A series of holes 38 in the side wall of the mounting 34 place the interior of this chambered mounting into direct communication with the bowl 28.

A fitting 40, having an opening 42 for a conduit 44, is held in place by the mounting 34 when the carburetor is assembled. This fitting 40 is thimble-like in form and has a shouldered flange 46

at its rim to lie between a shoulder 48 on the mounting 34 and a part of the casing 10.

A nozzle member 50 projects into the fitting 40 and its central bore receives the lower end of the conduit 44. This nozzle member 50 is held in place within the mounting 34 by machine screws 52 and a number of downwardly and inwardly inclined air passages 54 formed in the nozzle member 50 converge toward the axis of the air outlet passage 14 and the nozzle member 50.

It is clear therefore, as seen in Fig. 4, that the passages 54 within the nozzle member 50 place a mixing chamber 56 within nozzle 50 into communication with the outer extremities of the nozzle 50. The fitting 40 shrouds the nozzle member 50 to form a closed space 58 therearound which in turn receives heated air from a tubular member or pipe 60 that is fitted into an intake port 62 formed in the side wall of the fitting 40. This pipe 60 leads to any suitable source of heated air, and is preferably in communication with the exhaust manifold (not shown) of the engine with which the carburetor is used for receiving exhaust gases therefrom, and is insulated as shown to maintain the air within the pipe 60 in a heated condition until it reaches the space 58.

The mixing chamber 56 within the nozzle 50 is joined to a lower portion of the chamber in the mounting 34 through a plug 64, having a valve 66 reciprocably and freely movable therein. This valve is a tapered, pin-like member having a serrated head 68, and longitudinal movement of the valve 66 will feed a greater or lesser amount of fuel from the lower portion of the chamber in the mounting 34, into the mixing chamber 56.

An annular internal shoulder 70 on the nozzle member 50 is at the zone of juncture between the upper and lower portions of the mixing chamber 56. The portion of the mixing chamber 56 below this shoulder 70 is slightly greater in diameter than the portion of the mixing chamber 56 above the shoulder 70.

This shoulder 70 lies directly beneath the inner ends of the air passages 54, and when heated air entering through the air passages 50 impinges upon the upper surface of the shoulder 70, a turbulence is established and the upward suction on the surface of the fuel in the mixing chamber 56, insures an entrainment of fuel particles within the heated air streaming in through the passages 54 and thence upwardly through the conduit 14.

The maximum movement of the valve 66 is insufficient to force the head 68 against the under surface of the portion of the nozzle 50 forming the shoulder 70, unless upward suction assists the structure hereinatfer described and which is employed for motivating the valve 66. If, however, the valve 66 should be drawn upwardly into the mixing chamber 56, it will not escape because of the annular internal flange or head just described. Likewise, if the head 68 of the valve 66 should strike the inside of the nozzle member 50, it will not block the movement of fuel.

A collar 72, slidable upon the fitting 40, has a pair of diametrically opposed stubs 74 to receive a yoke 76, and a notch 78 extending upwardly from the lower edge thereof provides clearance for the tubular member 60 as the collar 72 slides on the fitting 40 through the action of the yoke 76. This yoke 76 is mounted upon a shaft 80 passing through the casing 10 and to a point exteriorly thereof where a choke lever 82 is affixed thereto.

A suitable fitting 84 is employed to join the

lever 82 with any manually manipulable instrumentality. A plunger 86 in engagement with a lateral extension 88 of the lever 82, is spring loaded and yieldably maintains the lever 82 in a position where the collar 72 (Fig. 4) is in a normal position.

A bracket cooperates with the collar 72 when choking of the carburetor is desired. This bracket comprises a pair of rods 90, a bridging member 92, supporting the valve 66 and an annular head or valve 94 formed to receive the annular lip of the collar 72 in creating a substantially air-tight joint.

The air outlet passage 14 of the casing 10 has an internal flange 96 with a diameter slightly less than the outside diameter of the valve head 94. Valve 94 is easily shifted along the internal flange 96 during the normal operation of the apparatus.

A spring loaded pin 98 extends through an opening provided in the casing 10, and the head of this pin lies against a cam face 100 on the lever 82. The function of these parts will be hereinafter definitely set forth.

Assuming the parts of the carburetor illustrated and above described to be in the position shown in the drawings, particularly Fig. 4:

The engine may be started with a rich mixture by moving the lever 82 to turn the shaft 80 and thereby elevate the collar 72, valve head 94, members 90 and 92 of the bracket, and manifestly, the valve 66 to allow the mixing chamber 56 to fill with fuel. Suction created in the engine will draw this fuel mixture out through conduit 14 and thence to the cylinders of the engine through the pipe 18 and the intake manifold, not here illustrated. No air will enter the pipe 18 from the air inlet 12, but as soon as the engine is started, the lever 82 will be returned to the normal position, shown in Fig. 2, to allow automatic operation.

When the lever 82 is moved, the cam 100 will force the pin 98 inwardly and into the path of travel of the valve head 94. Thus, a positive stop is established for the entire bracket, of which annular valve 94 is a part and no air can be drawn from the intake 12 because of the complete sealing-off of the air inlet 12 from the air outlet 14 by the internal flange 96, annular valve 94, and the collar 72. When the choke is released, however, the spring on the pin 98 will return the pin to the position shown in Fig. 4, and thereafter the entire bracket may reciprocate in response to suction and flow of air from the intake 12 to the outlet 14, and thence, the pipe 18.

As the engine runs, the valve 94 is lifted from the collar 72, and air passes into the mixing conduit 16, there to meet and mingle with the fuel and heated air mixture leaving the conduit 14. As the valve 94 is lifted in response to a greater flow of air, the valve pin 66 will be forced upwardly and thereby allow a greater amount of fuel to enter the mixing chamber 56 from within the lower chambered portion of the mounting 34.

As liquid fuel flows from within the lower portion of the mounting 34, the supply is replenished from the bowl 28 by way of the holes 38. The level of the fuel within the bowl 28 is maintained constant by the float 32 and its valve 34.

As the valve head 94 moves upwardly within the confines of the flange 96, air enters the outlet passage 14 between the annular lip of the collar 72 and the inner annular edge of the valve 94. After the valve 94 passes upwardly beyond the

confines of the flange 96, air floods in to the outlet passage 14 from the inlet 12, past both the inner and outer annular edges of the valve 94. Thus, as soon as the valve 94 passes the flange 96, the amount of air will suddenly and appreciably increase.

So contouring the inner face of the casing 10 along which the valve head 94 passes, prevents the possibility of binding or sticking and the rigid journaling of the rods 90 as shown, will further contribute to the ease of operation.

The flow of fuel into the bowl 28 will have no effect upon the bracket because its member 92 is confined within the mounting 34 where a quiescent condition prevails insofar as the fuel is concerned.

Manifestly, the actuation of the butterfly valve within the pipe 18 by actuating the shaft 22, will draw a greater or lesser amount of air through the carburetor and as soon as this air all traverses the mixing conduit 16, the fuel mixture emanating from the conduit 44 will never fail to mingle therewith.

Gases entering the space 58 from the exhaust manifold of the engine through the pipe 60 will move through the air passages 54 to be charged with fuel within the mixing chamber 56. There are preferably a number of these passages 54, and as indicated in my prior patent, the cross-sectional area of the conduit 44 is substantially the same as the combined cross-sectional areas of the passages 54.

It is clear from the foregoing that a continuous flow of heated air is introduced along the surface of the raw fuel within the mixing chamber 56, and as suction from the engine is created in the conduit 44, this heated air will be drawn from the pipe 60 and fuel will be moved from the chamber within the fitting 34 where complete carburation takes place in the mixing chamber 56 prior to movement of the mixture upwardly in conduit 44. It is well known by those skilled in the art that air and fluid can be more effectively combined if the air is preheated, and therefore, the fuel that emanates from the top of conduit 44 is not only entirely saturated with air, but this mixture is already heated as its passes into air flowing through casing 10 from air inlet 12 to air outlet 16. This insures that the final carburation will be complete before the mixture passes into the conduit 18 and thence to the engine.

These improvements not only eliminate the bulky and undesirable jacket that encased the pipe 18 for heating the mixture as disclosed in my prior patent, but makes for instant and effective combustion of the mixture in the engine since carburation is not as complete when heating of the mixture occurs after the air and fuel have been brought together.

This feature is particularly important in its function when choking occurs in the manner as set forth above. Since a rich mixture is desired for starting the engine, the air entering the inclined passages 54 will more effectively mix with fuel because of its preheating, than in my former patent wherein such air originated in the inlet passage 12.

Obviously the total air requirement of the engine should be greater than the total volume of air or gas that is permitted to flow through the pipe 60 so that the automatic opening of the valve head 72 will occur as above set down, and the size of the pipe 80 be determined accordingly.

Since a small amount of pressure will be present in the pipe 60, heated air will to a large extent be present in the space 58 at all times, thereby reducing the required amount of suction from the intake manifold that would otherwise be necessary, to draw this air or gas through the pipe 60.

It may be found in some instances that certain types of engines will create more pressure in the exhaust manifolds thereof than in other engines, thereby introducing all the air requirement of the engine at the space 58. Such condition would tend to effect the automatic operation of the bracket and its valve head 94 to the extent of not being actuated by suction of air from the air inlet passage 12. Therefore, a control valve 102, having an actuating lever 104, leading to a convenient point of access by the operator, is provided to vary the size of the opening through the pipe 60. This valve 102 is of the conventional type, mounted on the pipe 60 and having means within the pipe 60 to open and close the passage therethrough whereby the total volume of air passing into the space 58 can be kept below the total air requirement of the engine.

All of the aims and objects set forth at the outset in this specification are therefore made possible through the employment of a carburetor made in accordance with the above description and as shown in the accompanying drawings. It is obvious also that my present carburetor will operate in strict accordance with the principles set forth in U. S. Letters Patent No. 2,366,056, but with greater efficiency due to the improved arrangement of parts as herein set forth.

Having thus described my invention, what I claim as new and desire to secure by Letters Patent is:

In a carburetor having a hollow casing provided with a primary air intake port, an outlet, a bowl for fuel to be mixed with air, and a tubular member having a mixing chamber therein disposed to receive fuel from said bowl and to convey fuel and air mixture toward said outlet into the flow of air through the casing from said primary air inlet to said outlet, the improvement of which comprises the combination of a body surrounding a portion of said tubular member adjacent the mixing chamber thereof, presenting an air flow equalizing compartment separate from the flow of primary air through the casing; a valved conduit communicating at one end thereof with said compartment for directing secondary heated air to said compartment, said tubular member having a plurality of passages therein for placing said compartment into communication with said mixing chamber and disposed to direct heated air from the compartment toward the level of fuel in said mixing chamber.

ANDREW CRAIG RUSSELL.
